SYNTHETIC FOOD CASING

Richard A. Ottens, Downers Grove, Ill., assignor to Union Carbide Corporation, a corporation of New York

Continuation-in-part of design application Ser. No. 8,647, Sept. 19, 1967. This application Aug. 7, 1968, Ser. No. 13,052

Term of patent 14 years

Int. Cl. D5—03

U.S. Cl. D59—2

Fig. 1.

Fig. 2.

FIG. 3.

FIG. 1 is a plan view of a synthetic food casing showing my new design, the article is tubular and is shown in a flattened condition;

FIG. 2 is a plan view of the side opposite that shown in FIG. 1; and

FIG. 3 is an enlarged fragmentary view thereof.

This is a continuation-in-part of my application D. 8,647, filed Sept. 19, 1967 and now abandoned.

I claim:

The ornamental design for a synthetic food casing, as shown and described.
